UNITED STATES PATENT OFFICE.

JOSEPH B. WEAVER AND PETER PARKE, OF CHICAGO, ILLINOIS, ASSIGNEES TO THE PULLMAN COMPANY, OF CHICAGO, ILLINOIS, A CORPORATION OF ILLINOIS.

TRUCK-PEDESTAL.

1,400,586.

Specification of Letters Patent. Patented Dec. 20, 1921.

Application filed December 10, 1920. Serial No. 429,669.

To all whom it may concern:

Be it known that we, JOSEPH B. WEAVER and PETER PARKE, citizens of the United States, residing at Chicago, in the county 5 of Cook and State of Illinois, have invented certain new and useful Improvements in a Truck-Pedestal, of which the following is a specification.

This invention relates to railway rolling 10 stock, and pertains particularly to improvements in the construction of pedestals designed for incorporation in car trucks and the like. The present invention is directed primarily to the provision of a construction 15 whereby the pedestal may be formed entirely from commercial shapes, viz, flat plates and rolled bars, to provide a pedestal construction of adequate strength, and, on account of being made of rolled steel, of greater 20 flexibility than the cast pedestals usually employed in passenger equipment, thereby limiting the liability to breakage under the constant shocks to which pedestals in service are subjected. Another object of the in- 25 vention is to provide a pedestal construction in which the journal box guides, subject to wear, may be readily demounted for replacement when worn, and further to provide a pedestal which may be manufactured in 30 quantities at a very low cost and in different weights by the use of the same forming tool. To attain these objects certain new considerations must be met in order to provide for the disposal of materials to contribute the 35 necessary strength at the desired points, to provide for the mounting of the pedestal in the truck and to provide for the attachment of other members of the truck assembly in operative association with the pedestal.

40 Other and further objects and advantages of the invention will be pointed out hereinafter by reference to the illustrative form herein disclosed, will be indicated in the appended claims, or will be obvious upon an 45 understanding of the invention; and it is to be understood that the present disclosure is made for the purpose of illustrating the invention, and is not to be construed as limiting what we claim as our invention to the 50 particular embodiments shown.

In the accompanying drawings,

Figure 1 is a partial side elevation of a railway car truck illustrating the application of our improved pedestal construction;

55 Fig. 2 is a side elevational view of a truck

pedestal having a construction embodying our invention;

Fig. 3 is a side view of the same, but showing the parts in association with a wheel piece of the truck frame;

Fig. 4 is a horizontal section taken substantially on line 4—4 of Fig. 2.

Referring to the drawings by means of the reference characters applied, let it be understood that the numeral 1 designates the 60 wheel piece of a railway truck frame, with which are associated the journal box in which the wheels are mounted, and here illustrated by the journal box 2. As is well known in the art, it is the function of the 65 truck pedestal to connect the journal box with the truck frame so that the longitudinal movement imparted to the latter will be transmitted to the former to advance the 70 wheels in the progressive movement of the 75 car. Incident to this function, the pedestals must allow for the necessary relative vertical movement of the journal box and truck frame incident to compression and extension of the springs supporting the latter. 80 In our improved pedestal construction, for the attainment of the advantages and objects indicated above, we construct the pedestal of two major members formed from commercial plates of proper material and thickness. 85 One of these members is the suspension plate 4, and the other is the guide plate 5. The suspension plate 4 preferably is formed of considerably heavier stock than the guide plate 5, as it functions as the supporting 90 member whereby the pedestal is attached to the truck frame, in addition to its function as a lateral retaining member for the journal box; while the function of the guide plate 5 is to coöperate with the plate 4 in the lateral retention of the journal box and in the proper placing and bracing of the pedestal on the truck portion on which it is mounted. These plate members 4 and 5, obviously, may be made from any desired weight of stock, 100 so that a given set of dies may be utilized to produce pedestals having any desired variation in weight. These plate members are of inverted U shape, their downwardly extending portions 4^a and 5^a providing pedestal jaws, and the transverse portions connecting said jaws forming arches whereby the pedestal may be mounted on the truck frame. As will be observed in Fig. 2, the arch of the supporting plate is of consid- 105

110

erably greater height than that of the guide plate, so that it will extend a considerable distance across a side face of the wheel piece, and it is drilled at appropriate points to provide apertures for the seating of the connection bolts 4^b. The arch of the guide plate, on the other hand, is of proper height to extend partially across the opposite side face of the wheel piece, but it is shaped with reference to the location of the apertures 4^b so as to give the necessary clearances for the heads or nuts of the connection bolts. The two plate members thus formed are connected by top spacers 7 and bottom spacers 8. The top spacers are U shaped members having their arms 7^a connected to the inner faces of the plate members 4 and 5 by rivets, and having their transverse webs 7^b disposed horizontally and properly spaced with reference to the arch and jaw portions to constitute positioning members for determining the extent to which the wheel piece may be inserted between the plate members. The bottom spacers 8 are mounted by rivets at the lower extremities of the pedestal jaws, being connected to the plate members by lateral flanges 8^a, and having lower horizontal flanges 8^b. These flanges are suitably drilled for the mounting of bolts whereby the tie-strip may be connected to the pedestals in the customary fashion. In order to increase the stability of the connection between the plate members, through bolts 10 may be inserted through them and through the lateral flanges of the upper spacers adjacent the horizontal flanges 7^b, and drawn up tightly by nuts on lock washers; and to close the joints and provide desirable lateral bearing above the point of connection, the spacers may be joined to the plate members by electric welds as illustrated at "W." With the parts assembled in this manner it will be observed that the plate members constitute depending abutments spaced apart transversely and longitudinally. The outside plate member 4 constituting the main attaching member for the pedestal to the truck frame may be of greater thickness than the inner plate member 5, which functions principally as a tie plate, thereby affecting economy in construction. Upon these depending jaws are mounted the guides 11. These are formed of sections of bar material by the simple operations of shearing them off in proper lengths and drilling the rivet holes through jigs or with gang drills. The section of material employed for these guides is preferably a shallow angle having one relatively heavy and one relatively light flange, so that the latter will constitute an attaching flange 11^a adapted to abut the outer face of the plate members on which it is mounted, and the former will constitute wear flanges 11^b extending toward each other across the vertical margins of the plate mem-

bers. The wear flanges 11^b constitute contact members adapted for operative engagement against the sides and guide lugs of the journal box, and they are positioned parallel so that the journal box will be permitted the necessary vertical movement between the pedestal jaws. The contact members are made demountable so that by the simple operation of cutting off the rivets, the members when worn can be demounted for replacement. Due to the nature of the construction, however, with a given size of plate members, pedestals may be constructed for the accommodation of various sizes of journal boxes, simply by varying the relative spacing of the opposite guides on the pedestal jaws. This spacing, obviously, is determined by the location of the fastenings 12 whereby the guides are secured in place.

When the pedestal is mounted in the truck, the through bolts 4^b are passed through the apertures of the suspension plate and through suitable holes drilled in the wheel piece 1, and drawn up by nuts 6 so that the suspension plate has close abutment with the outer face of the wheel piece. The guide plate 5 is spaced a sufficient distance away from the inner face to clear it and allow for commercial variations in width of wheel piece castings. The nature 95 of the arch of the guide plate 5 permits the close abutment of the arch of the suspension plate with the outer face of the wheel piece, regardless of variations in width of wheel piece and without any distortion of the portions on opposite sides of the wheel piece, thereby contributing to the security and immobility of the mounting. The upper spacers coöperate with the lower face of the wheel piece to contribute the same results, and to maintain the proper clearance below the wheel piece for the operation of the end 3 of the equalizer, and may be secured to the wheel piece by means of vertical bolts 14. The equalizer extends through the 110 space between the upper and lower spacers and the plate members to its intended position on top of the journal box, and the form and disposal of the upper spacers is such as to permit the necessary vertical play of the 115 equalizers.

With the parts in place, the tie strip 13 is connected to the lower spacers 8 by bolts, and to the wheel piece, forming a lower retaining member for the pedestal jaws.

We have specified above some of the various advantages of this construction, and it is believed unnecessary to go farther into a description of its operation. It is to be observed, however, that in addition to the advantages hereinbefore indicated, the construction permits the disposal of all fastenings in such relationship as to utilize their greatest effective strength; that the material of the plate members is disposed in the 130

line of thrust from the journal box, and due to the integral unity of the jaws and arch portions, the stresses are not transmitted across joints. Furthermore, the 5 parts subjected to the greatest wear are demountable, so that they may be replaced when worn.

We claim:

1. In a truck construction, a pedestal comprising a front suspension plate having an upstanding connection arch adapted for connection to the truck wheel piece and depending jaw portions, a relatively thinner rear guide plate having an upstanding arch 10 portion and depending jaw portions, spacer members connecting said plates and means connecting the suspension plate to the wheel piece to support the guide plate.

2. In a truck construction, a pedestal comprising a suspension plate having an upstanding connection arch and depending jaw portions, means for attaching the connection arch to the truck wheel piece, a guide plate having depending jaw portions, 15 lower spacer members connecting the jaw portions of said plates and affording attaching points for the tie strip, and upper spacer members connecting said plates and affording abutments for the wheel piece, the 20 guide plate being supported solely through its connection with said spacer members and the suspension plate.

3. In a truck construction, a pedestal comprising a flat suspension plate and a relatively thinner guide plate, the former having an upstanding connection flange for attachment to the truck wheel piece and the latter being free from the wheel piece, both 25 said plates including depending jaw portions, and spacers connecting said plates, whereby the guide plate is supported on the wheel piece by the connection flange.

4. In a truck construction, a pedestal comprising a flat suspension plate and a flat 30 guide plate, the former having an upstanding connection flange for attachment to the truck wheel piece, both said plates including depending jaw portions, spacers connecting said plates, and guides demountably 35 supported on said jaw portions and overlapping the inner margins thereof.

5. In a truck construction a pedestal comprising a suspension plate and a guide plate disposed in parallel relationship, said suspension plate including an upwardly extending connection arch and depending 40

jaws, the guide plate having depending jaws alined transversely with corresponding jaws of the suspension plate, spacers connecting said plates, and separate guides demountably supported in parallel relationship on the respective jaws for coöperation with a journal box.

6. In a truck construction a pedestal comprising a flat suspension plate and a flat 45 guide plate disposed in parallel relationship, said suspension plate including an upwardly extending connection arch and depending jaws, the guide plate having depending jaws alined transversely with corresponding jaws 50 of the suspension plate, spacers connecting said plates, and bar sections mounted in parallel relationship on the respective jaws for coöperation with a journal box, said bar sections having transversely directed portions for coöperation with the journal box 55 guides.

7. In a truck construction a pedestal comprising a guide plate and a relatively heavier suspension plate, said suspension 60 plate having an upstanding connection arch arranged to abut the wheel piece, fastenings insertible through the connection arch and wheel piece, the guide plate having an upstanding portion arranged for association 65 with the opposite side of the wheel piece and shaped to clear said fastenings, and transverse connections maintaining said plates in parallel relationship.

8. In a truck construction a pedestal comprising a flat guide plate and a relatively heavier flat suspension plate, said suspension plate having an upstanding connection arch arranged to abut the wheel piece, fastenings insertible through the connection 70 arch and wheel piece, the guide plate having an upstanding portion arranged for association 75 with the opposite side of the wheel piece and shaped to clear said fastenings, transverse connection maintaining said plates in parallel relationship, and vertical guides carried by the respective plates for coöperation with a journal box.

In testimony whereof we have hereunto subscribed our names in the presence of two 80 subscribing witnesses.
